UNITED STATES PATENT OFFICE.

ERIC O. STROM, OF HILTON, NEW JERSEY.

WRAPPING MACHINE.

Application filed November 16, 1918. Serial No. 262,820.

To all whom it may concern:

Be it known that I, ERIC O. STROM, a citizen of the United States, and a resident of Hilton, in the county of Essex and State of New Jersey, have invented certain new and useful Improvements in Wrapping Machines, of which the following is a specification.

This invention relates generally to the art of preparing certain articles of merchandise for the retail trade by placing them separately in protective envelopes or containers, and it more particularly appertains to devices for individually encasing cigars in paper wrappers or the like.

One of the objects of the invention is to produce an improved device of the nature set forth that will efficiently perform the function of enclosing an article within a wrapper by conjoint rotation thereof, the ends of the latter meanwhile being held fast to effect twisted closures at the extremities of the former.

Another object is the production of a device of the type specified embodying a self-contained construction, with coactively moving parts so balanced relatively to each other that the insertion of the article and wrapper therebetween, as well as the retraction of the wrapped article therefrom, may be effected without previous or concomitant manipulation of the said parts, that is, independently of all extraneous control.

A further object is to provide a device of the species mentioned having a continuously moving feeder kept under uniform tension both by automatically acting and by manually adjusted mechanism.

Still another object is the provision of a device of the character described equipped with bearings and journals requiring a minimum amount of lubrication, and yet running quietly with the least possible friction.

A still further object is to construct a device of the kind referred to which shall be light and of small compass, strong and durable, composed of few and simple parts, and

amenable to low cost of production, as well as easily repaired.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawings, wherein like parts are designated by the same reference characters thruout the several views.

In the said drawings,—

Figure I is a top plan view illustrating a practical embodiment of the invention, certain parts thereof being omitted;

Fig. II is a side elevation of the same;

Fig. III is a longitudinal vertical section, on the line III—III of Fig. I;

Fig. IV is an end elevation, looking from the right-hand side of Fig. II; and

Fig. V is an enlarged transverse section of a detail.

Generally described, the invention comprises a light framework enclosing a series of rolls, over or around which runs an endless belt or apron, set in motion by a power-pulley attached to the shaft of one of these rolls. The series of rolls includes a pair arranged to support the article to be wrapped; a presser roll suspended thereabove and coacting therewith to wrap the envelope around the article by rotating them together; an idler roll serving to produce a gap between the rolls that support the article and wrapper during rotation; a tightener-roll that performs the double function of tensioning the endless belt and changing its course so as to cause it to run over the article and wrapper in a direction opposite to that of the supporting rolls thereunder; an equalizing roll located in the plane of the presser and of the idler; and the drive roll, above mentioned, to the shaft of which the power-pulley is affixed. Both the presser roll and the equalizing roll

are mounted in oscillatory frames and affected by weights attached to the same.

The advantages of the invention as here outlined are best realized when all of its 5 features and instrumentalities are combined in the one and same structure, but, useful devices may be produced embodying less than the whole.

It will be obvious to those skilled in the 10 art to which the invention appertains, upon becoming conversant with the details thereof, that the same may be incorporated in several different constructions. The accompanying drawings, therefore, are submitted 15 only as showing the preferred exemplification of the invention.

The form of the device under consideration includes oppositely located cheek-pieces or frame plates 1 and 2, that are held together in spaced relation, by shouldered studs 3, 4 and 5, with nuts engaging the threaded extremities thereof, as shown in the drawings hereto annexed. Adjoining the ends of the plates 1 and 2, on the outside, are angular legs 6 and 7, disposed in pairs, by means of which the said plates may be secured to a primary support, as at A, Fig. II. The support may be in the nature of a work-bench, or the like, adapted to 30 receive the lower halves of the frame plates.

Bearings 10 are attached to opposite sides of the plates 1 and 2, in proximity to the rear ends of the latter, and a shaft 11 is journaled therein. This shaft may be 35 driven, for instance, by a belt-pulley 12, secured to either one of its ends, as represented in Figs. I and IV. A collar 13, at the opposite end of the shaft, keeps it properly aligned in its bearings aforesaid.

40 Fixedly mounted on the shaft 11, between the plates 1 and 2, is a roll 14, which constitutes the main driver for an endless belt or apron 15, hereinafter more fully described. The latter-named element, as will 45 be observed, appears only in Fig. III, it being omitted from the other figures of the drawings to give a clearer view of the parts surrounded thereby, and consequently to avoid confusion.

50 Journaled directly in the frame plates 1 and 2, are three spindles 17, 18 and 19, which are maintained against axial displacement, each by a pair of opposed shield-like retainers 20, quasi-triangular in form 55 and held in place by screws, as 21. These retainers are provided with apertures 22, 23 and 24, offset relatively to the said spindles, so that the latter are overlapped at one of their edges, preferably the lower- 60 most, by the corresponding edges of the said apertures, as clearly seen in Fig. II. The several spindles are thereby kept in place, and further the apertures serve as oil-holes for their lubrication. Not only 65 are the ends of the spindles reached by the

lubricant in this way, but it also spreads to a pair of bushings 25, 26, revolvable thereon, which latter are shown in section in Fig. V. These bushings may be of fibre, or other suitable material, and are forced into the terminals of bores 27, 28 and 29, respectively formed in rollers 30, 31 and 32, through which the spindles are passed. The rolls 30 and 31 afford indirect supports for the article to be wrapped, while the roll 32 is 75 an idler. By removing either one or both of the retainers 20, the spindles can be withdrawn and the rolls taken out, without dismantling the frame plates.

Another roll 35 is located in rear of the 80 roll 31, in proximity to the main roll 14. The said roll 35 may be of slightly smaller diameter than the rolls 30, 31 and 32, previously referred to, and serves as a tightener for the belt 15, also before mentioned. The 85 internal construction of the roll 35 is similar to that of the said rolls, and includes a spindle 36, the ends of which are arranged to turn in bearings 37, adjustably clamped to the outer sides of the plates 1 and 2, near the upper edges thereof, for instance, by screws 38, centered through slots 39, in extensions 40, of the bearings 37. In order to hold these bearings in alignment, the extensions 40 are preferably formed integral therewith, and guided on short studs 41, received in the slots 39, in spaced relation to the screws 38. As shown by dotted lines in Fig. II, the frame plates are formed with elongated apertures 42, to admit of the spindle 36 being moved bodily therein, back or forth according to the required adjustment of the belt-tightening roll. Either bearing 37 may be advanced or retracted, as needed, to enable the roll 35 to pull more or less on one side of the belt than on the other, if necessary, in order to centre the belt with relation to the other rolls in the machine.

As will be noticed, particularly with reference to Figs. II and III, the aforementioned legs 7 extend upwardly above the plates 1 and 2, as at 45, and carry a pintle 46, upon which is hingedly supported one end of a three-sided frame 47. The open or free end of this frame is directed forward and carries a spindle 48, on which a presser roll 49 is revolvably mounted, through the medium of a pair of bushings similar to those hereinbefore described in connection with Fig. V. At the opposite or closed end 50 of the frame 47, beyond the supporting pintle or hinge thereof, may be applied a counterweight 51, or its equivalent, to balance or relieve the pressure exerted by the last-named roll in case the frame itself is 115 not sufficiently heavy to accomplish the same purpose. The counterweight is conveniently affixed to the closed end 50 of the frame 47 by means of a set-screw, as 52, engaging the rear one of a pair of jaws 53, de- 120 125 130

pending from the said counterweight and straddling the said closed end of the frame. As shown in Figs. I and III, the pintle 46 may be held against axial displacement by 5 split-pins 54, the removal of which enables the frame 47 and thereto connected parts to be readily taken out.

The direction of motion of the belt 15 running over the presser roll 49, taken in 10 conjunction with the pivotal disposition of the oscillatable frame 47 above the driving roll 14 tends to hold the said presser roll down in close proximity to the article to be wrapped resting upon those portions of the 15 belt which run over the supporting rolls 30 and 31.

In order to predetermine the height of the presser roll 49 above the subjacent rolls 30 and 31, there is provided a pair of adjusting stops 55, which may be in the nature of plates with inclined flanges 56, underlying the side members of the frame 47. These stops are adapted to rest at their bottom edges upon the bearing blocks 10, and are 25 held to the frame plates 1 and 2, exteriorly thereof, by screws 57, engaging slots 58, that permit the shifting of the stops relatively to the three-sided frame, so that it can either be raised or lowered.

30 Supported substantially in the vertical plane of the idler roll 32, and below the same, is an equalizing roll 61, which is revolvable through intermediate bushings, of the type before described, on a spindle 62, 35 rotatably fitted at its opposite extremities in the lateral members of a three-sided frame 63. The latter is open at the front end, which is oscillatably mounted on a pintle 64, carried by the plates 1 and 2, in proximity to and in advance of the forward stud 3. The rear, free end 65 of this frame is closed in the vicinity of the stud 4, where it is arranged to swing underneath the main roll 14, and holds up a suspended weight 66, 45 removably attached thereto, for instance, by means of a hook connection 67.

The pintle 64 is held against axial displacement by a split pin 68, the removal of which allows the pintle to be withdrawn 50 and the three-sided frame 63 detached from the device together with the equalizing roll 61.

The previously mentioned endless belt or 55 apron 15 is made of rubber, or other suitable material, and successively passes over the several rolls herein designated by the reference numerals 30, 32, 31, 35, 49, 14 and 61. The main roll 14 is preferably covered with a facing or lining 69, of yielding material, 60 to increase its driving adherence on the belt or apron.

Notches 72 are formed in the top edges of the frame plates 1 and 2, on opposite sides of the device, to afford a clearance for the 65 ends of the cigar or other article to be

wrapped, and which is supported upon the rolls 30 and 32. To provide additional room for the operator's fingers, the notches 72 may be chamfered on the outside of the frame plates, as indicated at 73, Fig. II. 70

For convenience in using the device, a small table is provided at the front thereof, as exemplified in Figs. I, II and III. This table may consist merely of a board secured to and partly embraced by the forward part 75 of the frame plates 1 and 2, adjacent to the roller 30. An extension 77 may also be added to this table, to furnish a support for the wrappers to be placed around the articles. The operator, may rest his or her arms on the work bench A while feeding the articles and their wrappers into the device. The extension 77 may be attached to the frame plates 1, 2 by means of side cleats 80, in a manner that is well understood. 85

As stated at the beginning of this specification, the improved machine herein described is particularly well adapted to the wrapping of cigars, and of course its operation will be better comprehended by reciting the manner in which the machine is used for placing wrappers around this class of articles. Assuming then that a certain quantity of cigars is conveniently at hand, with a pile 90 of wrappers on the table extension 77, and the machine is firmly set on a work-bench or the like, the operator will seat himself (or herself) in front of the said extension. Usually a cigar is taken hold of by one hand, and laid upon the top sheet of the wrapper pile in a direction transverse to the frames 95 1 and 2. Each wrapper consists, preferably of a substantially rectangular sheet of paper, of light texture and aseptic. The cigar is placed upon the near edge of the paper, which is partly turned around it preparatively to feeding into the machine. The power-pulley having been set in motion, and the endless belt or apron thereby caused to travel continuously in the various directions indicated by the arrows in Fig. III, the partly wrapped cigar is turned over so that the free edge of the wrapper trails behind the cigar which is then pushed sidewise between the bights of the endless belt that respectively cover the adjoining surfaces of the forward supporting roll 30 and the presser roll thereabove. The roll being about evenly balanced by the counterweight 51, bearing upon the remote end of the three-sided frame 47, it is sensitive to the lightest touch and rises at once, sufficiently to let pass the partly wrapped cigar without undue friction. The partly wrapped cigar then slides into the gap intermediate 100 of the parallel supporting rolls 30 and 31, 105

110 The roll being about evenly balanced by the counterweight 51, bearing upon the remote end of the three-sided frame 47, it is sensitive to the lightest touch and rises at once, sufficiently to let pass the partly wrapped cigar without undue friction. The partly wrapped cigar then slides into the gap intermediate of the parallel supporting rolls 30 and 31, 115 where it momentarily rests with its lower sides in contact with the traveling belt passing over these two rolls. As this occurs, the presser roll resumes its normal position at 120 125 130

the forward end of the counterweighted frame, predetermined by the location of the stops 55, which brings the section of belt running around the presser roll to bear upon 5 the uppermost side of the partly wrapped cigar, this belt section moving in an opposite direction to that followed by the belt portion carried at the time by the underlying rolls 30 and 31. Meanwhile, the ends of the 10 wrapper which project beyond the extremities of the cigar are held fast by the operator, with the result that the wrapper and cigar are rotated together by the oppositely running belt sections or portions and the 15 former is completely rolled about the latter. The cigar is then entirely incased, with the ends of the wrapper twisted at its opposite extremities. The final step in the operation is to withdraw the enwrapped cigar from 20 its temporary resting place between the presser roll and the supporting rolls. This is accomplished simply by pulling back the article the same way it was introduced, that is by retracting it past the presser roll sus- 25 pended at the front end of the counter- balanced frame. It is understood that in thus retracting the cigar, the operator holds only the twisted ends of its wrapper, so that no injurious pressure is exerted at any 30 time upon the cigar itself. The wrapped cigar having been withdrawn and deposited in some convenient place or receptacle, the operation is repeated with fresh wrappers and cigars in the manner just outlined. The 35 operation is simple and sufficiently expeditious, as a trained operator using a machine of the type herein disclosed can easily wrap several thousands of cigars in the course of a day's work.

40 While a certain preferred embodiment of this device has been shown and described, it will be understood that changes in the form, arrangements, proportions, sizes and details thereof may be made, without departing 45 from the scope of the invention as defined by the appended claims.

Having described my invention what I desire to secure by Letters Patent and claim, is:—

50 1. A device for individually wrapping articles, comprising in combination, a pair of supporting rolls, a coacting presser roll thereabove, a belt running with constant tension and contact over all of said rolls, a 55 driving roll for imparting continuous motion to said belt, and means for yieldably suspending said presser roll so as to enable it to recede from said supporting rolls by the insertion therebetween of an 60 article with its wrapper and the retraction of the wrapped article therefrom.

65 2. A device for individually wrapping articles, comprising in combination, a pair of supporting rolls, a presser roll oscillately suspended above the same, a con-

stantly tensioned belt enveloping the said rolls, a driving roll for said belt, the centre of oscillation of said presser roll being offset from that of said driving roll and assisted by the direction of motion of the belt 70 to urge the presser roll towards the supporting rolls, and means for limiting the range of oscillation of the presser roll relatively to the supporting rolls to keep it at a predetermined distance therefrom. 75

3. A device for individually wrapping articles, comprising in combination, a set of supporting rolls, a presser roll oscillatably supported thereabove, a belt arranged to run continuously over the said rolls, a driving roll for said belt, the centre of oscillation of said presser roll being above that of said driving roll and coacting with the direction of motion of the belt to urge the presser roll downward in proximity to said supporting rolls, and an equalizing roll below the latter engaging the belt to maintain a constant tension thereon when the presser roll recedes from or approaches the supporting rolls. 80 85

4. A device for individually wrapping articles, comprising in combination, a pair of supporting rolls spaced one from the other, a coacting presser roll yieldably mounted above the space between said supporting rolls, an automatically tensioned belt running over the said rolls, a driving roll adapted to impart continuous motion to said belt, and an idler and a tightener roll for the latter disposed in offset relation 100 to the supporting rolls. 95

5. A device for individually wrapping articles, comprising in combination, a pair of supporting rolls with a space therebetween, a presser roll yieldably mounted above said space, an automatically tensioned belt running over the said rolls, a driving roll for continuously moving said belt, an idler roll engaging the latter below the space intervening between said supporting rolls, and a tightener roll located to one side of the last named rolls. 105 110

6. A device for individually wrapping articles, comprising in combination, a pair of supporting rolls spaced from each other, 115 a presser roll yieldably mounted substantially central above the space between said supporting rolls, a belt arranged to run continuously over the said rolls, a driving roll for said belt disposed to one side of the above named rolls, an idler roll engaging the belt below said space, a tightener roll located intermediate of one of the supporting rolls and said driving roll, and an equalizing roll beneath said idler roll serving to 120 maintain a constant tension upon the belt. 125

7. A device for individually wrapping articles, comprising in combination, a pair of supporting rolls, a presser roll coacting therewith, a constantly tensioned belt run- 130

- ning over the above mentioned rolls, a driving roll for imparting continuous motion to said belt, an oscillatable frame carrying said presser roll, and means partly balancing 5 said frame to relieve the pressure of the latter named roll upon an article, rotated by oppositely running sections of the belt passing over the presser and said supporting rolls.
- 10 8. A device for individually wrapping articles, comprising in combination, a pair of supporting rolls, a presser roll yieldably suspended thereabove, a belt arranged to run continuously over the above named rolls, a 15 driving roll for said belt, an equalizing roll engaging the latter, an oscillatable frame constituting a mounting for said equalizing roll, and means for predetermining the pressure to be exerted by said frame in order 20 to maintain a constant tension upon the belt.
9. A device for individually wrapping articles, comprising in combination, a pair of supporting rolls, a presser roll coacting 25 therewith, a belt arranged to run continuously over the said rolls, a driving roll for said belt, a partly balanced frame for said presser roll mounted to oscillate above said driving roll, an equalizing roll engaging 30 the belt, and a pressure exerting frame oscillatably sustaining said equalizing roll below the driving roll to maintain a constant tension on the belt.
10. A device for individually wrapping 35 articles, comprising in combination, a pair of supporting rolls, a presser roll coacting therewith, a belt arranged to run continuously over the said rolls, an equalizing roll engaging the latter, and oscillatable frames 40 constituting mountings for said presser roll and said equalizing roll respectively, said frames being oppositely fulcrumed above and below said driving roll, the arrangement being such that as the frame for the presser 45 roll is being raised or lowered, the frame for the equalizing roll coincidentally ascends or descends to maintain a constant tension on the belt.
11. A device for individually wrapping 50 articles, comprising in combination, a pair of supporting rolls, a coacting presser roll thereabove, a constantly tensioned belt running over the before named rolls, a driving roll imparting continuous motion to said belt, a carrying frame for said presser roll fulcrumed to oscillate above said driving roll, and a stop movable relatively to said frame to predetermine the operative space 55 between the presser roll and said supporting 60 rolls.
12. A device for individually wrapping articles, comprising in combination, oppositely located frame members, supporting rolls revolvably mounted on spindles journaled in said members, a coacting presser 65 roll yieldably suspended above said supporting rolls, a belt running over the before mentioned rolls and retaining means overlying the ends of said spindles so that the latter and the supporting rolls thereon may be removed without interfering with said belt, said presser roll, or the frame members. 70
13. A device for individually wrapping articles, comprising in combination, oppositely located frame members, supporting rolls arranged to revolve in spaced relation between said members near the upper edges thereof, a coacting presser roll yieldably suspended above the space intermediate of said supporting rolls, a belt running over the said rolls, and a feed table carried by the frame members forwardly below said presser roll, in substantial alignment with the supporting rolls, whereby the article to be wrapped may be slid from said table directly 75 upon one of the supporting rolls and enabled to raise the presser roll until lodged in the space between all of said rolls.
14. A device for individually wrapping 80 articles, comprising in combination, a horizontally extended frame, a work table at the front end thereof, supporting rolls disposed transversely of said frame adjacent to said table, a coacting presser roll suspended above said supporting rolls, a belt arranged to run continuously over the said rolls, and a driving roll for said belt located at the rear of the frame away from the work table. 85
15. A device for individually wrapping 90 articles, comprising in combination, a horizontally extended frame, spaced supporting rolls and an idler roll thereunder having their spindles journaled in said frame, a presser roll coacting with said supporting rolls, an oscillatable carrier for said presser 95 roll fulcrumed above the frame at the rear end thereof, a belt arranged to run continuously over the said rolls, a driving roll for said belt mounted on a shaft rotatable in the frame below the fulcrum of said carrier, a tightener roll having the ends of its spindle fitted in bearings adjustably secured to the frame intermediately of said driving roll and the before mentioned rolls, and an equalizing roll pivoted to the frame in advance of and below said idler roll. 100
16. A device for individually wrapping 105 articles, comprising in combination, a pair of supporting rolls, a coacting presser roll thereabove, a belt passing over the before 110 named rolls, a driving roll imparting motion to said belt, a tightener roll located to one side of said supporting rolls, and means for laterally adjusting said tightener roll to centralize the running of the belt over all of 115 said rolls.
17. A device for individually wrapping 120 articles, comprising in combination, a pair of supporting rolls, a coacting presser roll thereabove, a belt running over the before 125 named rolls, a driving roll imparting motion to said belt, a tightener roll located to one side of said supporting rolls, and means for laterally adjusting said tightener roll to centralize the running of the belt over all of 130 said rolls.

mentioned rolls, a driving roll for said belt, a tightener roll for the latter, adjustable bearings at the opposite ends of said tightener roll, and means for independently adjusting the ends of the tightener roll thru said bearings so as to guide the belt over the several rolls.

18. A device for individually wrapping articles, comprising in combination, a pair 10 of supporting rolls, a coacting presser roll thereabove, a driving roll, a belt having its

inner side enveloping all of said rolls, and an idler roll engaging the outer side of said belt to change the direction of motion thereof from said presser roll to said supporting rolls, the arrangement being such that the the stretch of the belt passing under the presser roll travels towards the driving roll while that portion of the belt running over the supporting rolls moves oppositely. 15

ERIC O. STROM.
